UNITED STATES PATENT OFFICE.

FRANK HUDA, OF PERTH AMBOY, NEW JERSEY.

NON-SKID FOR TRUCKS.

1,302,373.

Specification of Letters Patent. Patented Apr. 29, 1919.

Application filed February 9, 1918. Serial No. 216,261.

To all whom it may concern:

Be it known that I, FRANK HUDA, a citizen of the United States, and a resident of Perth Amboy, in the county of Middlesex and State of New Jersey, have invented a new and Improved Non-Skid for Trucks, of which the following is a full, clear, and exact description.

This invention relates to non-skid devices for vehicle wheels and has particular reference to means for applying non-skid chains, or their equivalent, to commercial truck wheels.

Among the objects of the invention is to provide an attachment, which may be regarded as a permanent attachment, for the felly of a truck wheel, said attachment providing means for quickly attaching to the same a flexible chain device and for similarly detaching the chain therefrom according to the weather or condition of the roadway.

Another object of the invention is to provide a means for attaching or holding a non-skid chain to a wheel providing for the droppage therefrom of a broken chain so as to obviate any possibility of injury to an occupant of the vehicle or any other person adjacent thereto.

A still further object of the invention is to provide an attachment means for a non-skid chain for use in connection with wooden fellys and of such a nature as to protect the felly from abrasion or damage from the chain.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which

Figure 1 is a side elevation of a truck wheel indicating my improvement in practical use.

Fig. 2 is a vertical transverse section on the line 2-2 of Fig. 1 representing that

form of my invention applicable especially to rear wheels.

Fig. 3 is a vertical transverse sectional detail of my improvement adapted particularly for front wheels.

Fig. 4 is an inner face view of that form of the attachment shown in Fig. 2; and

Fig. 5 is a transverse section of a metal rim showing a modified form of my improvement applied thereto.

In the application of my device to a standard wooden felly of an automobile wheel said felly ordinarily being rectangular in cross section, I provide a clip 10 of a size substantially equal to the width and depth of the felly across the inner face of which the clip extends and having end pieces or tongues lying flat against the sides or faces of the felly. This clip 10 is made of a fairly heavy metal stock preferably as a drop forging and of sufficient strength to constitute the anchorage or base for the non-skid chain 11 of any suitable character having end links 12 and adapted to extend across the face or periphery of the wheel. Any suitable means may be provided to secure the clip in place upon the felly 13. For this purpose I show gimlet pointed screws 14 extending through the end pieces or tongues of the clip in practically the same horizontal direction parallel to the axis of the wheel. The screws may lie in alignment with each other or otherwise, and since no fastening means are required extending outward radially into the felly the matter of applying the device to the felly is a very simple one. In other words to apply the clip 10 to the felly all that is required ordinarily is to slip it over the felly, mark the points for the screws and then with a simple boring tool to start the holes the clip may be soon fastened securely by driving screws in from the sides, a simple expedient since there is no obstruction preventing this operation.

In all forms of the device applicable for wooden fellys it will be noted that the non-skid member 11 bears directly upon the end pieces or tongues of the clip in practice and so the wood work is shielded or protected from serious damage or abrasion so com-

monly incident to such devices with means heretofore used for securing the ends of the chains adjacent to the spoke and without protection where the chains bend over the edges of the felly.

With reference now to Figs. 2 and 4 the reader's attention is called to the means for attaching the end loops or links 12 of the chain providing for two direct results, 10 namely, the quick attachment of the chain and the free drop of a broken chain from the wheel. 15 indicates an anchor hook of peculiar construction, the same being detachably connected to the face of the clip that may be regarded as the inner face because it is directed toward the wheel hub. The clip adjacent to one corner is provided with an undercut socket 16 into which the point 17 of the hook 15 is projected with a 20 sort of pivotal action, the hook as a whole swinging essentially around the point of the hook as a pivot while the flat opposite end portion 18 of the hook swings toward the opposite side of the pivot and toward the flat face of the clip in position to be locked by means of a polygonal headed locking screw 19 tapped into the body of the clip at 20. A spring locking washer 21 may be employed, if desired, to prevent any possibility of loosening of the locking screw. 25 One of the links 12 of the chain is first slipped over the hook 15 and then the hook is applied as just described and locked. The opposite link 12 of the chain, however, is first hooked over the finger 22 or what may be called an open hook of strong rigid nature secured permanently by any suitable means as a heavy rivet 23 to the opposite end portion of the clip. The chain 11 will 30 be cut or provided of a length preferably just suitable for the link first to be hooked freely over the finger 22 and then passed around the tire with the second or opposite link 12 lying over the socket 16. The hook 15 is then put into place and locked as already described, making the attachment quick and secure through the operation of but a single screw 19. A small T-wrench, or its equivalent, may be employed 35 for manipulating these locking screws so that the operation may be quickly performed as indicated. It will be understood that so long as the chain remains intact it will be securely held upon the hook and finger. 40 If, however, the chain breaks, as frequently happens as a result of the normal operation of the truck, the broken part thereof on the side of the wheel having the finger 22 will drop freely from the finger while this portion of the wheel rises. The finger, therefore, is preferably applied on the side next to the vehicle body otherwise any person riding on the vehicle body adjacent to the wheel might be struck by the swinging of 45 the chain on that side. To remove the chain

when not required, the loosening of the single screw 19 suffices to permit such result by reversal of the steps above enumerated.

In the form shown in Fig. 3 the clip is provided with two undercut sockets 16 for 75 the accommodation of two hooks 15 as already described in detail. In this form of the invention both end links of the chain are securely anchored to the clip each by operation of a locking screw 19. With respect to the points 17 of the hooks 15 it will be appreciated that because of the peculiar co-operation between the same and the socket 16 full strength is provided for the hook and yet without gouging or boring into 80 the broad face of the felly. It will, of course, be understood that the clips are made in standard sizes to fit standard sizes of wheel fellys and hence the device is applicable to wheels of any size or make. 85

Fig. 5 shows that form of my improvement applicable to a metal felly or wheel rim, the inner face of which is indicated at 24, the sides at 25, and the spoke at 26. The clip 10' is shown fitted against the face 24, 90 and in this connection I wish it to be observed that with respect to any surface or part to which any form of clip is secured the clip will be shaped to correspond. The form of clip 10' is provided with the same 95 character of undercut socket 16 as has already been described for the accommodation of the point 17 of the hook 15, but since the clip 10' is in the nature of a flat plate or a plate that may be more or less curved 100 to conform to the surface to which it is applied and not having a tongue or portion embracing the side of the wheel it is secured to the metal structure preferably by means of two heavy machine screws 27 having heads countersunk at 28 within the clip and having the threaded portions tapped into holes 29 formed in the wheel member. The locking screw 19 is or may be just the same as has already been described the same 110 acting through the flat portion of the hook 15 into the clip. The operation of this form of the invention is just the same as has been described in connection with Fig. 3, the two end links of the chain being severally connected detachably to the two hooks 15 at 115 opposite sides of the wheel.

I claim:

1. The herein described attachment means for a non-skid chain, comprising a rigid clip having an undercut socket, anchor means carried by the clip to receive and hold the end links of the chain, one of said anchor means comprising a detachable hook having a point projecting into said undercut socket beyond the main orifice of said socket and abutting the undercut walls of the same, and a detachable fastener to lock said hook in holding position against the face of the clip thereby holding the point 130

of the hook in interlocking position in the socket.

2. The herein described attachment means for a non-skid chain, the same comprising a member having formed in the body thereof an undercut socket, a hook having a point which after passing through a link of a chain is introduced into said socket by tilt-

ing movement and adapted to project beyond the main orifice of the socket and abutting against the undercut walls of the same, and a detachable fastener to secure the portion of the hook remote from the point of the hook against the face of the member. 10

FRANK HUDA.
